UNITED STATES PATENT OFFICE.

FRED A. RISBERG, OF CHICAGO, ILLINOIS.

STITCHING-MACHINE.

1,140,531.

Specification of Letters Patent. Patented May 25, 1915.

Application filed May 20, 1914. Serial No. 839,817.

To all whom it may concern:

Be it known that I, FRED A. RISBERG, a citizen of the United States, residing at Chicago, in the county of Cook, State of Illinois, 5 have invented certain new and useful Improvements in Stitching-Machines, of which the following is a specification.

The present invention relates generally to stitching machines and more particularly to 10 the mechanism for positioning the work with reference to the stitching mechanism.

It has been the practice heretofore in positioning pamphlets, magazines and other work which required stapling or other 15 stitching, to position each piece of the work, for a given run, at the same point relative to the stitching mechanism. As a result, when the pieces of work are piled up for trimming or other purposes, the correspond- 20 ing stitches in the several pieces lie in the same vertical lines and therefore increase the height of the pile at those points considerably beyond its height along the edges to be trimmed. Because of this, the trim 25 is not square or otherwise accurate unless the piles be kept small. In the latter event, the cost of handling is greatly increased over what it would be if larger piles could be used.

30 The object of the present invention is to provide mechanism by which the different pieces of work will be stopped in different positions relative to the stitching mechanism so that the stitches will be applied in different relative positions in the different pieces. By thus staggering the stitches, the work 35 may be more compactly piled for trimming. In such case, the corresponding stitches or staples do not lie, as before, in a single vertical line, but in a plurality of vertical lines. Consequently, many more pieces of work can 40 be put in the same pile and still a satisfactory trim obtained. Because of the ability to make the piles higher, the cost of han- 45 dling is greatly reduced.

In carrying out my invention, I preferably provide a shiftable stop which can be shifted so as to engage different pieces of the work in different positions relative to 50 the stitching mechanism. In this way the stitches or staples in the different pieces of the work are staggered and the advantages heretofore set forth are obtained.

For a full understanding of the invention, reference should be had to the following detailed description taken in connection with 55 the accompanying drawings.

The scope of the invention will be particularly pointed out in the appended claims.

In the drawings I have illustrated my in- 60 vention in association with the assembling and folding mechanisms of a printing press structure.

Figure 1 is a plan view of a portion of such press structure to which my invention 65 is applied; Fig. 2 is a side elevation of the same; Fig. 3 is a side elevation of a portion of the mechanism shown on an enlarged scale; Fig. 4 is a view of the gearing by which certain portions of the mechanism are 70 operated, parts being shown in section taken on a plane indicated by the line 4—4 of Fig. 1; Fig. 5 is a side elevation of the guideway mounting of one of the shiftable fingers; and Fig. 6 is a transverse vertical section 75 of the same taken on a plane indicated by the line 6—6 of Fig. 5.

Throughout these views like characters refer to like parts.

Referring to the drawing in detail, 10 and 80 11 indicate the side frames of the printing press structure upon which the various parts are mounted. These parts include a collecting cylinder 12 upon which the work is received at regular intervals from the 85 assembling portion of the press (not shown). From the cylinder 12 the work is passed along over the delivery cylinder 13 into the tape pathway formed by a pair of tapes 14 coöperating with a pair of tapes 90 15. These tapes are located along the edges of the work support or table 16 and carry the assembled sheets, which are to be stitched, forward to the stitching mechanism 17. As the work advances the shift- 95 able stop fingers 18 come into play to position it with reference to the stitching mechanism, as will be more fully described hereinafter. As soon as the staples or other stitches have been affixed, the work is again 100 advanced by means of the tapes 14 and 15, assisted by the drop rolls 19, until it encounters the stop 20 when beneath the folder knife 21 and above the folder rolls 22 and 23. By the operation of the fold- 105 ing knife 21 the sheets which have been

stapled or otherwise stitched, are folded on the line of stapling by the knife 21 forcing the sheets down between the rolls 22 and 23 in the usual way.

5 Any suitable collecting means may be provided for assembling the different sheets which are to be bound together and then delivering the same to the cylinder 12. Illustrations of such means are shown in United 10 States Patent No. 1,008,568, granted November 14, 1911 to E. P. Sheldon, and No. 1,048,746, granted December 31, 1912 to H. S. Schroeder.

The cylinder 12 has its shaft mounted on 15 the side frames 10 and 11 and is provided with a gear wheel 24. The delivery cylinder 13 is similarly mounted and provided with a gear wheel 25 meshing with the gear wheel 24. The tapes 14 pass over suitable 20 tape rollers mounted upon shaft 26, also journaled in the side frames 10 and 11 and provided with a gear wheel 27. These tapes also pass over rollers carried by swinging 25 arms 28 secured to the end member 29 of the frame structure. The coöperating tapes 15 pass over the driving cylinder 13, guide roller 30, and tape rollers mounted upon the brackets 31 beneath the arms 28. Rollers 32, 33 are mounted upon the table 16 so as 30 to engage the upper stretch of the tape 15 below the drop rolls 19 and the adjustable rollers 34, respectively.

The rollers 34 are mounted on arms 35 which are adjustably secured upon a shaft 36 which is secured at opposite ends to the side frames 10 and 11. These rollers 34 may be adjusted toward and from the rollers 33 so as to give sufficient pressure to the tapes to carry the work along over the table. The 40 drop rolls 19 are mounted upon crank arms 37 secured to a shaft 38 which is likewise journaled at its opposite ends in bearings mounted on portions of the side frames 10 and 11. The shaft 38 is also provided with 45 a crank arm 39 which is connected at its outer end to a forked connecting rod 40. The latter is provided with a cam roller 41 at its forked end, which coöperates with cam 42 upon a shaft 43 which also is journaled at its opposite ends in the side members 10 and 11 and which is further provided with a beveled gear wheel 44 on the outside of the member 11. As the shaft 43 rotates, the connecting rod 40 rocks the shaft 55 38, and, as a result, the drop rolls 19 are moved toward and from the coöperating rollers 32 so as to apply or withdraw pressure from the tapes. These drop rolls 19 are located so as to engage the tapes where the latter engage the work adjacent to the stop fingers 18. The drop rolls operate to apply pressure at the time the fingers 18 are lifted up and in so doing insure a quick and positive starting of the work from the position 60 65 in which it was stitched.

The stop fingers 18 consist of strips of spring metal, which are secured at their fixed ends to a guide 45, which works in a guideway 46, which is secured to a transverse rock shaft 47, which is journaled in a portion 48 of the framework of the stitching mechanism 17 and in a frame member 49 also associated with the stitching mechanism. The rock shaft 47 is provided with a crank arm 50, which is connected by a link 51 with a crank arm 52 upon the shaft 38. Thus both the drop rolls 19 and the fingers 18 are given their rocking motion from the shaft 38. The parts are so related that the fingers 18 are moved out of engagement with the table 16 as the rolls 19 are moved into engagement with the tapes. The guideway 46 upon the shaft 47 carries a forked guide 53 which extends downward and forward into position to engage the work and hold it 80 down against the table. The forked ends of the guides 53 respectively embrace the work-engaging end of the fingers 18. As the shaft 47 is rocked, the guides 53 are also lifted sufficiently to permit the work to advance under the pull exerted by the tapes. 85

By reason of the fingers 18 being secured to the guides 45, those fingers may be shifted back and forth with reference to the guideway 46 and the rock shaft 47 so as to 90 bring their work-engaging ends into different positions relative to the stitching mechanism 17. This shifting of the fingers 18 is brought about by cam actuated connections. In each case the guide 45 is provided with 100 an upward extension 54 by which it is pivotally connected to the end of a link 55 which is secured at its opposite end to the outer end of a crank arm 56 mounted to rotate freely upon the shaft 47. This crank 105 arm 56 is connected at a point near the shaft 47 with one end of a link 57 which is connected at its opposite end to a crank arm 58 upon a shaft 59, which is suitably mounted in the frame of the machine. There are two 110 such sets of connections. The shaft 59 is rocked through the agency of a crank arm 60, a forked connecting rod 61 and a cam 62 which engages the cam roller 63 on the connecting rod. The cam 62 is mounted on a 115 stud shaft 64 secured to a portion of the frame member 10 and is provided with a gear wheel 65 which is in mesh with the gear wheel 66 upon shaft 43. Thus, as shaft 43, through cam 42 and its connections, rocks shaft 47, so shaft 64, through cam 62 and its connections, reciprocates the fingers with reference to rock shaft 47. As here shown, the gear wheels 65 and 66 bear a ratio of 2 to 1 so that the fingers 18 engage the same 120 point of the table 16 upon every other actuation of the rock shaft. As a result of this to-and-fro movement of the fingers 18, every other pamphlet or piece of work has its 125 staples or stitches in one position, while the 130

intermediate pieces have their staples or stitches in an alternate position. When the work is stacked up, the stitches therefore appear as indicated at 66^a in the pile of pamphlets beneath the folding rollers in Fig. 2.

The folder knife 21 is mounted upon connected bell crank levers 67, 68 journaled respectively upon shafts 69 and 70 extending between the frame members 10 and 11. A 10 crank 71 and forked connecting rod 72 operate with a cam on shaft 43 to actuate the folder knife in proper time relation to the rest of the mechanism.

In the gearing shown in Fig. 4, the gear 15 wheel 24 by which the collecting cylinder is rotated, may be driven from any suitable source. This wheel is in direct mesh with gear wheel 25 which drives the collecting cylinder. Upon the same shaft is gear 20 wheel 74 which meshes with gear wheel 27 which drives the tape rollers. Upon the same shaft as gear wheels 25 and 74 is a gear wheel 75, which is in mesh with a gear wheel 76 upon a stud shaft 77 extending outward from the frame member 11. The stud shaft 77 carries a beveled gear 78 which meshes with a beveled gear 79 upon a shaft 80 suitably journaled in brackets upon the frame member 11. The forward end of the 25 shaft 10 carries a beveled gear wheel 81 which meshes with the beveled gear wheel 44 on the shaft 43. By means of this gearing, the feeding, folding, stitching, delivery and stop mechanisms are driven and 30 maintained in the desired time relation to each other. In this description, the stitching mechanism 17 has not been described in detail, nor its driving mechanism indicated, because the same forms no part of the present invention, but it and its timed relation to the feeding, delivery and folding mechanisms are old in the art.

In carrying out my invention, it will be apparent that many alterations and modifications may be made in the structure herein disclosed without departing from the spirit and scope of my invention. I, therefore, do not wish to limit myself to the specific matter disclosed but aim to cover all such alterations and modifications by the terms of the appended claims.

What I claim as new and desire to secure by Letters Patent of the United States is:—

1. In a stitching machine, the combination 55 of a work support along which work is adapted to be fed, stitching mechanism operatively related to said support, work-engaging stops on opposite sides of said stitching mechanism and operative to engage said support in a line transverse to the direction of feed to position the work relatively to said stitching mechanism, an actuating shaft substantially parallel to said line, an independent support on said shaft for each of 60 said stops, and means for shifting said

stops relatively to said shaft to change the positions of different pieces of work relative to said stitching mechanism.

2. In a stitching machine, the combination 70 of a work support, stitching mechanism operatively related to said support, a stop for engaging the work to position it relative to said stitching mechanism, a delivery device for conducting the work from the stitching mechanism, means for bringing 75 said device into operative relation to the work at regular intervals, and means bearing a timed relation to said bringing means for shifting said stop to change the position of the work relative to said stitching mechanism. 80

3. In a stitching machine, the combination 85 of a work support along which the work is adapted to be fed, stitching mechanism operatively related to said support means for conveying the work along said support, means for supplying the work at intervals to said conveying means, work-engaging stops on opposite sides of said stitching mechanism and operative to engage 90 said support in a line transverse to the direction of feed to position the work relatively to said stitching mechanism, an actuating shaft substantially parallel to said line, an independent support on said shaft 95 for each of said stops, and means bearing a timed relation to said supplying means for shifting said stops relatively to said shaft to change the positions of different pieces of work relative to said stitching mechanism. 100

4. In a stitching machine, the combination 105 of a work support, stitching mechanism operatively related to said support, a rock shaft, a stop finger movably secured to said shaft, means for rocking said shaft at regular intervals to bring said finger into engagement with said support to stop the work in operative position relative to said stitching mechanism, and means bearing a timed 110 relation to said rocking means for moving said finger transversely of said shaft to change the position of the engagement of said finger with said support and thus change the position of the work relative to said stitching mechanism. 115

5. In a stitching machine, the combination 120 of a work support, stitching mechanism operatively related to said support, a rock shaft, a stop finger movably secured to said shaft, work conveying tapes at opposite sides of said support, drop rolls for engaging said tapes to deliver the work from said stitching mechanism, means for actuating said drop rolls at regular intervals and means bearing a time relation to said roll actuating means to shift said stop finger relative to said shaft to change the position of the work relative to said stitching mechanism. 125 130

6. In a stitching machine, the combination of a work support, stitching mechanism operatively related to said support, work conveying tapes at opposite sides of said support, means for supplying work at intervals to said tapes, a rock shaft, a stop finger movably secured to said shaft, and cam actuated mechanism bearing a time relation to said supplying means for shifting 10 said finger transversely of said shaft to change the position of the work relative to said stitching means.

7. In a stitching machine, the combination of a horizontal work table, conveyer 15 tapes at the edges of said table for conveying the work along said table, stitching mechanism positioned near the center of said table, a transverse rock shaft in line with said stitching mechanism, guideways 20 secured to said rock shaft, stop fingers mounted to slide in said guideways, drop rolls for engaging said tapes, means for supplying the work at intervals to said tapes, a cam and connecting means for actuating 25 said fingers in said guideways, a cam and connecting means for rocking said rock shaft and moving said drop rolls, and gearing connections between said cams and between said cams and supplying means

whereby a timed relation is maintained between the operations of the associated parts. 30

8. In a stitching machine, the combination with a work table, stitching mechanism and work feeding means; of a work 35 engaging stop mechanism including a rock shaft, a guideway secured to said shaft and extending transversely thereof, a stop finger mounted to slide in said guideway; and a cam and connecting means for rocking said shaft and actuating said finger in said 40 guideway.

9. In a stitching machine, the combination of a work support along which work is adapted to be fed, stitching mechanism operatively related to said support, a stop 45 finger for the work having only one plane of movement and that plane extending in the direction of the feed of the work, and means for shifting said finger in the plane of its movement to vary its work-engaging position to variously position the work relative to said mechanism.

In witness whereof, I hereunto subscribe my name this 9th day of May, A. D. 1914.

FRED A. RISBERG.
